PNEUMATIC GAGING MACHINE FOR SELECTING ROLLS ACCORDING TO SIZE

Blaise L. Diamond, Detroit, Mich., assignor to
Tyson Bearing Corporation, Massillon, Ohio, a
corporation of Delaware

Application May 26, 1945, Serial No. 596,016

13 Claims. (Cl. 209—32)

1 My invention relates to roll gauging machines particularly adapted for gauging rolls for tapered roller bearings, and more particularly the invention relates to a combined roll gauging and selecting machine, whereby rolls passing through the machine are gauged and selected into a plurality of groups according to their respective sizes.

In usual roll gauging machines, either electrical contact or mechanical contact or friction means have been used at each gauging station, requiring relatively complex electrical circuits and electrically actuated roll selecting means, or relatively complicated roll selection mechanisms, or friction gauging means subject to wear during continuous use and being relatively difficult of adjustment in order to select rolls within very close diametrical limits.

The objects of the present invention include the provision of an improved roll gauging machine, preferably in the form of a combined roll gauging and selecting machine, and in which the gauging is effected by pneumatic or dynamic fluid means, and in which the selecting is likewise effected by pneumatic or dynamic fluid means, whereby a simplified arrangement and construction of the improved machine may be attained, whereby high precision roll gauging and selecting operations may be carried out, and whereby adjustments and maintenance of the machine are relatively easy and economical.

The foregoing and other objects are attained by the roll gauging machine, parts, combinations, and sub-combinations, which comprise the present invention, the nature of which is set forth in the following general statement, and preferred embodiments of which together with their mode of use are set forth by way of example in the following description, and which are particularly and distinctly pointed out and set forth in the appended claims forming part hereof.

The nature of the improved roll gauging and selecting machine of the present invention may be stated in general terms as including a base, and a turntable operatively mounted for rotation on the base about an axis extending upwardly and downwardly and which is preferably vertical.

The turntable is preferably of the general form of a large cone for a tapered roller bearing and having an upper conical side face below which extends radially outwardly an annular rib having a conical upper face at an acute angle with the conical side face.

Arcuate sections of the turntable conical side face and rib each constitutes a roll seat having a roller end support provided by the conical side

face and a roll end support provided by the rib.

An air ejecting duct is provided on the turntable for each roll seat, each air ejecting duct having a discharge opening at one side of the roll seat and an intake opening located to sweep over portions of the base.

An air supply duct is provided in the base and has an outlet opening located for registry with the air ejecting duct intake opening, and the base air supply duct also has an inlet opening.

A gauging nozzle is mounted on the base, and the gauging nozzle has a chamber and a chamber discharge opening directed across the roll end support and towards the roll side support of the roll seat.

Means are provided for supplying compressed air to the gauging nozzle chamber, and differential pressure operated valve means are interposed between the gauging nozzle and the base. The differential pressure operated valve means include a valve, differential pressure operated valve opening and closing means operatively connected with the nozzle chamber and with the valve, a valve inlet and a valve outlet for the valve, a duct connecting the valve outlet with the base air supply duct inlet opening, and means for supplying compressed air to the valve inlet.

A pressure gauge may also be communicatingly connected with the gauging nozzle chamber and the pressure gauge and the differential pressure operated valve opening and closing means each constitute means actuated by pressure changes in the gauging nozzle chamber, the pressure changes being produced by a roll on a roll seat being transported across the air jet ejected from the nozzle.

By way of example, embodiments of the improved combined roll gauging and selecting machine and improved parts therefor of the present invention are illustrated in the accompanying drawings forming part hereof, in which

Figure 1 is a top plan view of one embodiment of the improved roll gauging and selecting machine;

Fig. 2, an enlarged elevation view of one of the improved gauging nozzle assemblies of the machine, with portions in section as on line 2—2, Fig. 3;

Fig. 3, schematic fragmentary vertical sectional views of assemblies and parts of the machine arranged to show their operative relationship with each other; and

Fig. 4, an enlarged fragmentary top plan view similar to Fig. 1, with portions broken away for

more clearly illustrating details of construction and arrangement.

Similar numerals refer to similar parts throughout the several views.

The improved roll gauging machine indicated generally by 10 includes stationary members indicated generally by 11 provided with an upwardly opening tapered bearing sleeve 12 whose inner bearing surface 13 is conical with its larger base end at the upper end 14 of the bearing sleeve 12. The end face 15 of the bearing sleeve 12 is horizontal and is perpendicular to the vertical axis indicated by the dot-dash line 16 of the conical inner surface of the bearing sleeve 12.

A generally circular rotatable roll carrying table indicated generally by 17 has a lower flat face 18 in rotary bearing abutment with the upper face 15 of the bearing sleeve 12, and from the lower face 18 of the roll carrying table 17, a conical stem 19 extends downwardly and has an outer conical surface 20 fitting in rotary bearing abutment with the inner conical bearing surface 13 of the bearing sleeve 12. The rotatable table 17 and its bearing stem 19 thus are rotatably mounted in the bearing sleeve 12, and are operatively connected by means not shown for power drive rotation about the vertical axis 16, and such operative connection and power drive means may be similar to that set forth in the S. A. Strickland U. S. Patent No. 1,882,374.

The roll carrying table 17 is generally in the shape of a relatively large cone for a tapered roller bearing, and formed with peripheral portions including an upper conical surface 21 having a larger lower end 22 below which extends outwardly an annular rib portion 23 of the table 17 having upper faces 24 including portions in a conical surface at an acute angle with the conical surface 21, so that a tapered roll for a roller bearing for being gauged by the gauging machine 10 may be seated as indicated by dot-dash lines 25 in Fig. 3 with its large end down and resting on the rib surfaces 24 and with one element of its conical side surface resting against the conical surface 21.

At each of a plurality of circumferentially spaced roll seating stations on the peripheral portions of the roll carrying table 17, there is formed in the table 17 an air ejecting duct, which as shown includes a horizontally and radially extending bore section 26 whose outer circular end 27 terminates in the conical surface 21 at a location spaced above the rib 23. The inner end 27' of the bore section 26 connects with the side of the upper end 28 of a slanting bore section 29 extending downwardly and outwardly to a lower end opening 30 in the lower face 18 of the roll carrying table 17.

For the purposes of the present improvements, the lower face 18 of the annular table 17 has formed therein a plurality of downwardly opening arcuate grooves 31, each connecting with the lower end 30 of one of the bore sections 29.

The stationary members indicated generally by 11, as shown, include around the upper end of the bearing sleeve 12 and below the grooves 31 and duct or bore openings 30, a circular ring member 32 having a flat upper face 33 continuous with the upper face 15 of the bearing sleeve 12, and the flat upper face 33 of the ring member 32 is thus in bearing abutment with the lower face 18 of the rotating table 17.

The ring member 32 has formed therein a plurality of slanting bores 34 each having an

upper end 35 which registers with the grooves 31 and the lower ends 30 of the bore sections 29 of the table 17 during rotation thereof. Each bore 34 has a lower end 36 in the bottom face 37 of the ring member 32.

The stationary members 11, as shown, furthermore include below the ring member 32, a larger ring member 38 having an upper face 39 whose inner portions abut against the lower face 37 of the ring member 32, and there is formed in the ring member 38 a plurality of vertical bores 40, each having an upper end 41 connecting with the lower end 36 of one of the bores 34, and each bore 40 having a lower end 42 within the body 15 of the ring member 38. There is also formed in the ring member 38 for each of the vertical bores 40, a horizontal bore 43 having an inner end 44 connecting with the side of the lower end 42 of the paired vertical bore 40, and each horizontal bore 43 as shown terminates in the outer cylindric side face 45 of the ring member 38 in an enlarged internally threaded counter-bore 46.

On the top of the ring member 38, are mounted a plurality of circumferentially spaced gauge nozzle assemblies each indicated generally by 50 and including an inverted U bracket 51 having a transverse base 52 secured to the ring member 38 upon the top face 39 thereof and radially spaced beyond the side peripheral faces of the roll carrying table 17. From opposite ends of the transverse base 52 there extend upwardly parallel legs 53, and in the upper end of each parallel leg 53 is formed a horizontal bearing bore 54 aligned with the bore 54 in the opposite leg 53.

A nozzle mounting block 55 extends between the upper ends of the legs 53 and is mounted therebetween for rotation about a horizontal axis, as shown by means of a trunnion cap screw 56 for each leg 53, the trunnion cap screw 56 extending through the bearing bore 54 of its mounting leg 53, and being screwed into a suitable threaded socket formed in the adjacent end of the mounting block 55.

The mounting block 55 as shown preferably has flat parallel faces 57 on opposite sides of its horizontal axis of rotation, and a cylindrical bore 58 extends through the mounting block 55, the axis of the cylindrical bore 58 preferably intersecting the horizontal axis of rotation of the mounting block 55, and the axis of the cylindrical bore 58 also preferably being in a radial plane passing through the vertical axis of rotation 16 of the table 17.

Each gauging nozzle assembly 50 furthermore includes a gauging nozzle indicated generally by 60 and including an elongated tube 61 having formed therein a bore 62. The tube 61 is provided with external threads 63 extending from the discharge end 64 of the tube 61 to an enlarged connector head 65. The threaded portion of the tube 61 extends and fits in the bore 58 of the mounting block 55, and nuts 66 screwed on the threads 63 of the tube 61 on opposite sides of the mounting block 55 provide for longitudinal adjustment of the nozzle 60 towards and away from the turntable 17.

In a threaded counterbore in the discharge end 63 of the tube 61 is screwed a nozzle tip 67 having a nozzle chamber discharge opening 68 formed therein. In a counterbore 69 formed in the rear end of the nozzle head 65 there is screwed a plug 70, and the bore 62 of the nozzle 60 between the nozzle tip 67 and the plug 70 constitutes a nozzle chamber.

In a suitable counterbore 71 on the top of the nozzle head 65 is communicatively connected a dial pressure gauge indicated generally by 72 which is of usual construction and includes a usual hand which visually indicates changes in pressure in the nozzle chamber 62.

On the opposite lower side of the head 65 in a counterbore 71' is screwed a diaphragm operated electric switch indicated generally by 73, which is of usual construction, and includes a differential pressure actuated diaphragm 74 at one side of a chamber 75 which communicatively connects with the gauging nozzle chamber 62. The diaphragm 74 has a mechanical connection with an electric switch 76 which is series connected in an electric circuit including power conductors 77 and 78 and a solenoid actuated valve indicated generally by 79 of usual construction.

The valve 79 includes walls forming a valve chamber 80, valve sleeve means 81 operatively mounted in a vertical bore communicating with the valve chamber 80, the valve sleeve means 81 having an upwardly extending stem 82 which is provided on its upper end with an armature 83 above a solenoid coil 84. The valve chamber 80 has an inlet 85 and an outlet 86. Below the base ring member 38 is provided a pipe ring manifold 87 to which compressed air is supplied as through pipe 88.

The valve inlet 85 of each solenoid actuated valve 79 is communicatively connected with the manifold 87, as shown by an elbow 89, a nipple 90, and a T 91 in the pipe ring manifold 87. Each valve outlet 86 is connected by a duct 92 with the internally threaded counterbore 46 at the inlet opening of one of the base air supply ducts formed by the horizontal bore 43, the vertical bore 40, and the slanting bore 36.

As shown in Figs. 1 and 4, each base air supply duct formed by the bores 43, 40, and 36 is in a vertical plane extending through the vertical axis of rotation 16 of the turntable 17, and angularly displaced from the vertical plane including the longitudinal axis of the associated nozzle 60.

The turntable 17 rotates in the direction of the arrow 93. A roll drive pin 94 may extend radially from the conical surface 21 of the turntable 17 at the trailing side of each air ejecting duct end 27. Each arcuate groove 31 in the lower face 18 of the turntable 17 extends in the advancing direction from the lower end 30 of its associated bore section 29.

The base air supply duct bores 43, 40, and 36 are angularly displaced from the nozzle 60, so that each air ejecting duct opening 27 passes the nozzle tip 67 before the arcuate groove 31 for the particular air ejecting duct sweeps across the upper end 35 of the base air supply duct and until the air ejecting duct opening 27 has cleared the nozzle tip 67.

In operating the improved roll gauging and selecting machine 10, portions of the turntable 17 adjacent each air ejecting duct 27 constitutes a roll seat having a roll side support formed by a portion of the turntable conical side surface 21 and a lower roll end support formed by a portion of the rib 23.

From a broad standpoint the turntable 17 thus includes a plurality of laterally connected roll seats, each roll seat having an associated air ejecting duct. The discharge opening 68 of each nozzle chamber 62 is directed across the rib 23 and towards the conical surface 21 of the turntable 17. Each nozzle tip 67 is thus adapted to direct a jet of fluid, preferably compressed air

towards a roll to be gauged and selected, and carried on one of the roll seats of the turntable 17. Such a roll is shown by dot-dash lines 25 in Figs. 3 and 4.

If the roll to be gauged and selected passing any particular nozzle tip 67 is of such size as to build up a sufficient back pressure in the nozzle chamber 62, the hand of the pressure gauge 72 will visually indicate such back pressure, and the diaphragm 74 of the diaphragm operated electric switch 73 will close the switch 76 energizing the solenoid and opening the valve sleeve 81 of the valve 79, whereby compressed air from the manifold 87 will flow into the base air supply ducts and out through the turntable air ejecting duct opening 27 when the particular groove 31 passes over the base air supply duct upper end opening 35.

Each nozzle 60 has its own separate compressed air supply duct 85 admitting compressed air to its chamber 62. Above each set of base air supply duct bores there may be provided a roll receiving trough 96 into which any particular roll falls which is ejected from the turntable 17.

By suitable longitudinal adjustments of the several nozzles 60, the improved roll gauging and selecting machine gauges and selects at each gauging nozzle 60 any rolls having a particular diameter within predetermined limits which are carried past the particular nozzle tip 67 on the roll seats of the turntable 17.

The embodiments of the present invention illustrated and described herein are by way of example, and the scope of the present invention is not limited to the same or to the particular details thereof, but is commensurate with any and all novel subject matter contained herein which may at any time properly come under the United States patent laws be set forth in the claims hereof or originating herein, and the elements of any such claims are intended to include their functional and mechanical equivalents.

I claim:

1. In a roll gauging machine and the like, a base, a turntable operatively mounted on the base for rotation about an upwardly and downwardly extending axis, a roll seat on the turntable at one side of the axis of rotation, an air ejecting duct on the turntable, the air ejecting duct having a discharge opening at one side of the roll seat and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed towards the path of the roll seat on the turntable and the roll seat including a roll side support opposite the gauging nozzle discharge opening and a lower roll end support between the roll side support and the gauging nozzle discharge opening, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.
2. In a roll gauging machine and the like, a base, a turntable operatively mounted on the

base for rotation about an upwardly and downwardly extending axis, a roll seat on the turntable at one side of the axis of rotation, the roll seat including a roll side support and a lower roll end support, an air ejecting duct on the turntable, the air ejecting duct having a discharge opening in the roll seat side support and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed across the path of the lower roll end support of the roll seat and towards the path of the roll side support of the roll seat, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

3. In a roll gauging machine and the like, a base, a turntable operatively mounted on the base for rotation about an upwardly and downwardly extending axis, a roll seat on the turntable at one side of the axis of rotation, the roll seat including a roll side support facing away from the axis of rotation and a lower roll end support extending beyond the roll side support and away from the axis of rotation, an air ejecting duct on the turntable, the air ejecting duct having a discharge opening in the roll seat side support and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed across the path of the lower roll end support of the roll seat and towards the path of the roll side support of the roll seat, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

4. In a roll gauging machine and the like, a base, a turntable operatively mounted on the base for rotation about an upwardly and downwardly extending axis, a roll seat on the turntable at one side of the axis of rotation, the roll seat including a roll side support and a lower roll end support, an air ejecting duct on the turntable, the air ejecting duct having a discharge opening in the roll seat side support and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed radially of the axis of rotation and across the path of the lower roll end support of the roll seat and to-

wards the path of the roll side support of the roll seat, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

5. In a roll gauging machine and the like, a base, a turntable operatively mounted on the base for rotation about an upwardly and downwardly extending axis, a roll seat on the turntable at one side of the axis of rotation, the roll seat including a roll side support facing away from the axis of rotation and a lower roll end support extending beyond the roll side support and away from the axis of rotation, an air ejecting duct on the turntable, the air ejecting duct having a discharge opening in the roll seat side support and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed radially towards the axis of rotation and across the path of the lower roll end support of the roll seat and towards the path of the roll side support of the roll seat, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

6. In a roll gauging machine and the like, a base, a turntable operatively mounted on the base for rotation about an upwardly and downwardly extending axis, the turntable having a peripheral side face and an annular rib below the peripheral side face, an air ejecting duct on the turntable, the air ejecting duct having a discharge opening in the peripheral side face and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed across the path of the rib and towards the path of the peripheral side face, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

7. In a roll gauging machine and the like, a base, a turntable operatively mounted on the base for rotation about an upwardly and downwardly extending axis, the turntable having a peripheral side face conforming to a surface of revolution about the axis and an annular rib below

the peripheral side face, an air ejecting duct on the turntable, the air ejecting duct having a discharge opening in the peripheral side face and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed across the path of the rib and towards the path of the peripheral side face, means for supplying compressed air to the gauging nozzle chamber, and differential pressure operated valve means including a valve, differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

8. In a roll gauging machine and the like, a base, a turntable operatively mounted on the base for rotation about an upwardly and downwardly extending axis, the turntable having a conical side face and an annular rib below the conical side face, an air ejecting duct on the turntable, the air ejecting duct having a discharge opening in the conical side face and an intake opening located to sweep over portions of the base, an air supply duct in the base having an outlet opening located for registering with the air ejecting duct intake opening and the base air supply duct having an inlet opening, a gauging nozzle on the base, the gauging nozzle having a chamber and a chamber discharge opening directed across the path of the rib and towards the path of the conical side face, means for supplying compressed air to the gauging nozzle chamber, and differential pressure operated valve means including a valve differential pressure operated valve opening and closing means operatively connected with the gauging nozzle chamber and with the valve, a valve inlet and a valve outlet for the valve, a duct connecting the valve outlet with the base air supply duct inlet opening, and means for supplying compressed air to the valve inlet.

9. In a roll gauging machine and the like, a base, a turntable operatively mounted on the base for rotation about an upwardly and downwardly extending axis, a plurality of roll seats on the turntable, each roll seat being at one side of the axis of rotation and including a lower side support and a lower roll end support, a plurality of air ejecting ducts on the turntable, each air ejecting duct having a discharge opening on one of the roll seat side supports and an intake opening located to sweep over portions of the base, a plurality of air supply ducts in the base, each air supply duct having an outlet opening located for registering with the air ejecting duct intake opening and each base air supply duct having an inlet opening, a plurality of gauging nozzles on the base, each gauging nozzle having a chamber and a chamber discharge opening directed across the paths of the lower roll end supports of the roll seats and towards the paths of the roll side supports of the roll seats, means for supplying compressed air to each gauging nozzle chamber, and differential pressure operated valve means for each gauging nozzle, each differential pressure operated valve means including a valve, differential pressure operated valve opening and closing means operatively connected with the associated

gauging nozzle chamber and with the valve, a valve inlet and a valve outlet for the valve, a duct connecting the valve outlet with the base air supply duct inlet opening, and means for supplying compressed air to the valve inlet.

- 5 10. In a roll gauging machine and the like, a base, a turntable operatively mounted on the base for rotation about an upwardly and downwardly extending axis, a plurality of roll seats on the turntable, each roll seat being at one side of the axis of rotation and including a lower side support and a lower roll end support, a plurality of air ejecting ducts on the turntable, each air ejecting duct having a discharge opening on one of the roll seat side supports and an intake opening located to sweep over portions of the base, a plurality of air supply ducts in the base, each air supply duct having an outlet opening located for registering with the air ejecting duct intake opening and each base air supply duct having an inlet opening, a plurality of gauging nozzles on the base, each gauging nozzle having a chamber and a chamber discharge opening directed across the paths of the lower roll end supports of the roll seats and towards the paths of the roll side supports of the roll seats, means for supplying compressed air to each gauging nozzle chamber, and differential pressure operated valve means for each gauging nozzle, each differential pressure operated valve means including a valve, differential pressure operated valve opening and closing means operatively connected with the associated gauging nozzle chamber and with the valve, a valve inlet and a valve outlet for the valve, a duct connecting the valve outlet with the base air supply duct inlet opening, means for supplying compressed air to the valve inlet, and means adjustably mounting each gauging nozzle for varying the location of its chamber discharge opening with respect to the turntable and the roll seats thereon.

- 15 25 30 35 40 45 50 55 60 65 70 75 11. In a roll gauging machine and the like, a plurality of laterally connected roll seats, each roll seat including a roll side support and a lower roll end support, means for transporting the roll seats successively past a gauging station, a gauging nozzle at the gauging station, the gauging nozzle including a chamber and a chamber discharge opening directed across the paths of the roll seat end supports and towards the paths of the roll seat side supports, means for supplying fluid under pressure into the gauging nozzle chamber so that a fluid jet is discharged from the nozzle chamber discharge opening, differential pressure operated means communicatingly connected with the gauging nozzle chamber, and means for ejecting a roll from each roll seat, the roll ejecting means being actuated by the differential pressure operated means.

12. In a roll gauging machine and the like, a plurality of laterally connected roll seats, each roll seat including a roll side support and a lower roll end support, means for transporting the roll seats successively past a gauging station, a gauging nozzle at the gauging station, the gauging nozzle including a chamber and a chamber discharge opening directed across the paths of the roll seat end supports and towards the paths of the roll seat side supports, means for supplying fluid under pressure into the gauging nozzle chamber so that a fluid jet is discharged from the nozzle chamber discharge opening, differential pressure operated visual gauge means communicatingly connected with the gauging nozzle chamber, and differential pressure actuated roll

11

ejecting means for each roll seat, each differential pressure operated roll ejecting means being operatively connected with one of the gauging nozzle chambers.

13. In a roll gauging machine and the like, a plurality of laterally connected roll seats, each roll seat including a roll side support and a lower roll end support, means for transporting the roll seats successively past a gauging station, a gauging nozzle at the gauging station, the gauging nozzle including a chamber and a chamber discharge opening directed across the paths of the roll seat end supports and towards the paths of the roll seat side supports, means for supplying fluid under pressure into the gauging nozzle chamber so that a fluid jet is discharged from the nozzle chamber discharge opening, differential pressure operated means communicatingly con-

10

nected with the gauging nozzle chamber, means for ejecting a roll from each roll seat, the roll ejecting means being actuated by the differential pressure operated means, and means adjustably mounting each gauging nozzle for varying the location of its chamber discharge opening with respect to the paths of the roll seats.
